Des. 212,641
Patented Nov. 5, 1968

212,641

LAMP BASE

Linda A. Mok and Louis A. Mok, both of 150 N. Arnaz
Drive, Beverly Hills, Calif. 90211

Filed Apr. 22, 1968, Ser. No. 11,539

Term of patent 14 years

(Cl. D48—20)

FIG. 1

FIG. 6

FIG. 5

FIG. 4

FIG. 3

FIG. 2

FIG. 1 is a perspective view of a lamp base showing our new design;

FIG. 2 is a top view thereof;

FIG. 3 is a left front elevation view thereof;

FIG. 4 is a left rear elevation view thereof;

FIG. 5 is a right front elevation view thereof; and

FIG. 6 is a right rear elevation view thereof.

The light socket and switch shown in broken lines in FIG. 1 are disclosed for illustrative purposes only.

We claim:

The ornamental design for a lamp base, substantially as shown and described.
